(73) Assignee: **Royal Appliance Mfg. Co.**, Cleveland, OH (US)

(57) CLAIM

(**) Term: **14 Years**

The ornamental design for a cap for dirt cup of a vacuum cleaner, as shown and described.

(21) Appl. No.: **29/116,903**

DESCRIPTION

(22) Filed: **Jan. 12, 2000**

FIG. 1 shows a cap for dirt cup of a vacuum cleaner showing our new design;

(51) LOC (7) Cl. **15-05**

FIG. 2 is a top plan view thereof;

(52) U.S. Cl. **D32/25**

FIG. 3 is a right side elevational view thereof;

(58) Field of Search D32/25, 30, 22;

FIG. 4 is a left side elevational view thereof;

15/320, 322, 323, 347, 350-353

FIG. 5 is a bottom plan view thereof;

(56) References Cited

FIG. 6 is a front elevational view thereof; and,

U.S. PATENT DOCUMENTS

FIG. 7 is a rear elevational view thereof.

D. 343,707 1/1994 Dyson .

The vacuum cleaner illustrated in broken lines in FIG. 1 shows the environment in which the cap for dirt cup for a vacuum cleaner according to the present invention is used and forms no part of the claimed design.
